UNITED STATES PATENT OFFICE.

SEVERIN RICHARDSEN, OF STRØMMEN, NORWAY.

AIRSHIP.

Application filed December 29, 1926, Serial No. 157,830, and in Norway April 23, 1926.

This invention relates to an airship without any gas filling or bearing plane and wherein the raising is effected by means of motor power. The invention is characterized substantially in the arrangement of a sufficient number of vertical screws which are placed in tubes passing through the hull vertically and further a sufficient number of horizontal screws also arranged in tubes 10 passing through the hull lengthwise.

In the drawings an example of carrying out the invention is shown.

Figure 1 is a side view in longitudinal section on the line I—I of Figure 2.

Figure 2 is a cross section on the line II—II on Figure 1.

Figure 3 is a detail view of the ship seen from the rear and showing a perforated tube for watering purposes.

Figure 4 is a detail view of the ship seen from the rear showing the use of skids.

The airship consists of a cigar-shaped hull 1, which in its longitudinal centre plane is provided with preferably 6 vertical screws 2, 3, 4, 5, 6 and 7, placed in fixed tubes 9, 10, 11, 12, 13 and 14 extending through the entire hull. Said tubes are at the lower part preferably a little widened to make the entrance of the air easier. The screws are extended over the hull to enable them to better catch the air. The shafts 16 of the screws are supported at their upper ends in a longitudinal beam 17 fixed to the hull and at their lower ends in transversals 18. Each shaft is provided with a worm 19 meshing with a wormwheel 20 mounted on a long shaft 21 arranged lengthwise in the hull. This shaft is provided with a sprocket wheel 23 with chain 24 leading to a sprocket wheel 25 mounted on the motorshaft 26. The motor 27 is fixed on the floor 28 which is arranged at a suitable height from the ship's bottom 29 in such a manner that under the floor a compartment 30 is left, which for example can be filled with water, when the ship is to be used for watering purposes or the like and in this case there may be arranged outside the hull a perforated tube 33 which is connected to the water compartment. In the lower part of this compartment there may be arranged separate containers 34 and 35 for water ballast, when the ship is used on sea. At the lower part of the ship there are arranged lengthwise

preferably two screws 40 and 41 for the longitudinal propulsion of the ship. These screws are arranged in tubes 42 and 43 stretching through the entire hull and are at the rear at the air discharge end somewhat flattened to provide a flat stream of air in order to act more efficiently upon the rudder 44, which is placed between the tubes. The rudder may be connected with a suitable steering apparatus, which is placed in a steering house 45 on the top of the ship. The shafts 46 and 47 of the screws are provided with sprocket wheels 48 and 49 with chain 50 in such a way that the screws are moved simultaneously. The shaft 46 is provided with a sprocket wheel 51 with chain 52 running to a wheel 54 mounted on the shaft 55 of the motor 56.

In front the ship is provided with a turnable ring 60 having four openings two of which 61 (one shown in the drawing) register with openings 62 for the inlet to the tubes 42 and 43 for the horizontal screws 40 and 41. The two other openings 72 are arranged at the lower part of the ring and are destined to register with the openings 63 for vertical tubes 64, which are leading down to the horizontal screws and are to be used when the ship is going on sea, as the usual inlet openings for the horizontal screws must then be closed to prevent the entrance of the waves. Such closing is obtained by means of ring 60, which to this end is turned about 180° so that the openings 61 are moved away from the openings 62 of the tubes 42 and 43 at the same time as the lower openings 72 will register with the openings 63 for the vertical tubes 64 in order to enable access of air to the screws 40 and 41.

The ship is provided with wheels 66 in order to enable it to be moved on the shore. Further the ship may be provided with wide skids 67 for use on snow, and in this case there may be arranged driving-screws of a larger diameter than it would be necessary for air-traffic.

The vertical screws can be made with a diameter of 1.20 m. and the horizontal screws with a diameter of for instance 0.75 m.

The arrangement of the screws in tubes passing through the entire hull has the advantage that the air current from the screws will not act depressing upon the hull, but

will pass without any hindrance through the ship. Thereby the ship is always maintained in a correct upright position.

I claim:

5. 1. An airship heavier than air, comprising a hull, horizontal and vertical channels through the same, air screws in said channels for supporting and moving the airship, said horizontal channels being flattened at 10 their rear end, and a side rudder between the rear ends of said horizontal channels. 45
2. An airship heavier than air, comprising a hull, horizontal and vertical channels through the same, air screws in said channels for supporting and moving the airship, 15 said hull at the front being provided with a turnable ring having four openings of which the two lower ones register with the openings for the inlets to the horizontal 20 channels for the horizontal screws and the two other openings are arranged at the upper part of the ring and are destined to register with openings for vertical tubes leading down to the horizontal screws. 60
3. An airship heavier than air, comprising a hull, horizontal and vertical channels through the same, air screws in said channels for supporting and moving the airship, said vertical screws being extended 30 over the hull to enable them to better catch the air, above said screws a longitudinal beam fixed to the hull forming a support for the upper ends of the shafts of said screws, transversals in the vertical channels forming supports for the lower ends 35 of said shafts. 65
4. An airship heavier than air comprising a hull, horizontal and vertical channels through the same, air screws in said chan- 70

nels for supporting and moving the airship, 40 said vertical screws being extended over the hull to enable them to better catch the air, above said screws a longitudinal beam fixed to the hull forming a support for the upper ends of the shafts of said screws, transversals in the vertical channels forming supports for the lower ends of said shafts, each of said shafts being provided with a worm meshing with a wormwheel mounted on a long shaft arranged lengthwise in the hull, said long shaft being provided with a chain leading to a sprocket wheel mounted on the motorshaft, said motor mounted on the floor. 50

5. An airship heavier than air, comprising a hull, horizontal and vertical channels through the same, air screws in said channels for supporting and moving the airship, said horizontal channels being flattened at their rear end, and a side rudder between the rear ends of said horizontal channel said rudder being connected with a suitable steering apparatus placed in a steering house on the top of the ship. 55

6. An airship heavier than air, comprising a hull, horizontal and vertical channels through the same, air screws in said channels for supporting and moving the airship, said vertical screws being extended over the hull to enable them to better catch the air, 75 means arranged above said screws and fixed to the hull forming a support for the upper ends of the shafts of said screws, and means in the vertical channels forming supports for the lower ends of said shafts. 75

In testimony whereof I have signed my name to this specification.

SEVERIN RICHARDSEN.
